CLAIM

The ornamental design for the non-glare, non-reflective screen magnifier, as shown and described.

DESCRIPTION

FIG. 1 is a front elevational view of a non-glare, non-reflective screen magnifier, showing my new design; FIG. 2 is a rear-elevational view thereof; FIG. 3 is a top-plan view thereof; FIG. 4 is a bottom-plan view thereof, showing a VELCRO tack strip at the bottom of an attachment board; FIG. 5 is a side-elevational view thereof, it being understood that the right and left sides are mirror images of one another; and, FIG. 6 is a top, front perspective view, the broken line showing of a computer screen and keyboard is for illustrative purposes only and forms no part of claimed design.
